CLAIM

The ornamental design of an organizer for cosmetic articles and the like, as shown and described.

DESCRIPTION

FIG. 1 is a top, front, and left side perspective view of an organizer for cosmetic articles and the like showing my new design;

FIG. 2 is a right side elevational view thereof, the left side being a mirror image of that shown;

FIG. 3 is a rear elevational view thereof; and

FIG. 4 is a top plan view thereof.

FIG. 1

FIG. 2

FIG. 4
